UNITED STATES PATENT OFFICE

171,841

CIGARETTE HOLDER

Bailey P. Cox, Dallas, Tex.

Application August 31, 1953, Serial No. 26,632

Term of patent 14 years

(Cl. D85—8)

To all whom it may concern:

Be it known that I, Bailey P. Cox, a citizen of the United States, residing at Dallas, in the county of Dallas and State of Texas, have invented a new, original, and ornamental Design for a Cigarette Holder, of which the following is a specification, reference being had to the accompanying drawing, forming part thereof.

The dominant features of my design are shown by full lines.

I claim:

The ornamental design for a cigarette holder, as shown and described.

BAILEY P. COX.
